CLAIM

The ornamental design for a display stand, as shown and described.

DESCRIPTION

FIG. 1 is a front, top, and left perspective view of a display stand showing my new design;

FIG. 2 is a back, top, and right perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

Broken lines are used to illustrate features of the display stand that form no part of the claimed design.

1 Claim, 8 Drawing Sheets(56)
